UNITED STATES PATENT OFFICE.

LOUIS F. PERKETT, OF TRAVERSE CITY, MICHIGAN.

HUMIDOSTAT.

1,060,786.

Specification of Letters Patent.

Patented May 6, 1913.

Application filed April 16, 1912. Serial No. 691,213.

To all whom it may concern:

Be it known that I, LOUIS F. PERKETT, a citizen of the United States, residing at Traverse City, in the county of Grand Traverse and State of Michigan, have invented a new and useful Humidostat, of which the following is a specification.

The present invention relates to improvements in humidostats, the primary object 10 of the invention being the provision of an electrically operated humidostat, provided with mechanism whereby the humidostat will accurately measure and indicate the degree of humidity in the atmosphere and 15 at the same time place into and out of operation vaporizers so that the air may be supplied with vapor to the desired humidity, the device operating automatically to cut out the vaporizers when the atmosphere is 20 of the desired humidity, the present device being especially adapted for use in vaults, residences and public buildings to maintain a uniform humidity at all times.

A further object of the present invention 25 is the provision of a humidostat provided with means actuated due to the humidity in the air to operate a pointer in conjunction with a setting pointer, the setting pointer and the metal of the humidostat being connected in an electrical circuit with also connected therein the desired number of vaporizers, thus providing a means for throwing into actuation the vaporizers when the humidity in the atmosphere is below normal 30 or the desired degree, and for automatically cutting out the vaporizers when the atmosphere has been supplied with the desired amount of vapor.

With the foregoing and other objects in 40 view which will appear as the description proceeds, the invention resides in the combination and arrangement of parts and in the details of construction hereinafter described and claimed, it being understood 45 that changes in the precise embodiment of the invention herein disclosed can be made within the scope of what is claimed without departing from the spirit of the invention.

In the drawings—Figure 1 is a top plan 50 view of the complete humidostat. Fig. 2 is a side elevation thereof. Fig. 3 is a section taken on line 3—3 of Fig. 1, with an electrical circuit containing the batteries and vaporizers shown in diagram and in oper- 55 able relation to the humidostat. Fig. 4 is a bottom plan view of the dial support show-

ing the humidity actuated members. Fig. 5 is a section taken on line 5—5 of Fig. 4 inverted. Fig. 6 is a section taken on line 6—6 of Fig. 4. Fig. 7 is a section taken on line 7—7 of Fig. 4. Fig. 8 is an elevation of the lever actuated pointer. Figs. 9 and 10 are detail views of the humidostat actuated pointer.

Referring to the drawings, the numeral 65 1 designates a circular casing, which is provided with the apertures 2, whereby the atmosphere may enter the casing to affect the actuating mechanism. The rim 3 of the casing is so formed as to carry the main 70 support and dial 4, while removably fitting upon the rim 3, is a rim 5 carrying the face glass plate 6 of usual construction. Disposed concentrically in the glass plate 6 is an aperture 7, the purpose of which will 75 presently appear.

In Fig. 4, the mechanism actuated, by the humidity of the atmosphere, is clearly shown and consists of the post 8 extending from the under side of the plate 4, said post 8 being provided with the screw 9 and thumb nut 10 for the adjustable connection of the L-shaped bracket 11, which is connected to the expandible strip 12. The other end of this strip 12 is provided with a pivoting 85 coupling 13 which is pivotally connected to one end of the double lever or arm 14, which as clearly shown is pivoted in the bracket 15 intermediate of its ends, said bracket 15 being connected to and depending from the under side of the plate 4. The opposite end of the lever 14 has pivotally connected thereto, the coupling 16 of the other expandible strip 17, while the other end of the expandible strip 17 is provided with a pivoting coupling 95 18 connected to the adjustable screw lever 19. The screw lever 19 is pivoted in the bracket 20 connected to and depending from the under side of the plate 4 and upon the opposite end thereof has pivotally and adjustably mounted thereupon, the milled disk 21, which is provided with an eye 22 for the connection of the flexible strip 23. This flexible strip 23 is connected as at 24, to the pointing hand arbor 25 of the humidostat, 100 the lower end of said hand being journaled in the bracket 26 connected to and depending from the under side of the plate 4. By this means it will be seen that any expansion and contraction of the expandible strips 12 110 and 17 will impart a movement to the flexible connection 23 and consequently to the

pointing hand arbor 25, which has placed upon the upper end thereof, above the dial 4 and under the face plate, the pointing hand 27. By this means, the degree of the 5 humidity of the atmosphere will be indicated by the pointer 27 in combination with the dial scale, as clearly shown in Fig. 1.

The pointer 27 is provided with the spring contact plate 28 and the pin 29, which is 10 slidably mounted in the pointer and connected to the spring, and said contact plate is so disposed as to bear upon the under side of the ring 35 of the manually actuated pointer 34, the purpose of which will presently appear.

The ring 30 is provided with a plurality of fixed arms 31 constituting a spider that is connected to any portion of the frame or the glass cover and is provided with means 20 for the connection of one terminal of the electrical circuit.

An arbor 32 is journaled for rotation in the aperture 7 of the glass face plate 6 and is provided with the operating milled head 25 33. Upon the inner end of said arbor 32 is carried the pointer 34, which as before stated is provided with the ring 35, a portion of which is incased by the segment 36 of insulation, which is connected thereto by means 30 of the pin 37.

The spring 28 of the pointing hand 27 is normally in contact with the ring 35 of the hand 34, as clearly shown in Fig. 3, and when riding upon the insulating segment 36, as will later appear, no electrical connection is made, but when the hand 27 is moved too far in one direction and engages the metal portion at the respective end of the segment 36, the circuit is closed to 40 include the batteries 38, conductors 39 and 40 and the vaporizers 41. As soon, however, as the pointing hand 27 is rotated, due to the strips 12 and 17, to have its spring plate 28 placed into contact with the insulation 45 36, the circuit will be opened and the vaporizers are cut out and cease operation.

In order to properly operate the humidostat, the same being electrically connected as shown in diagram, in Fig. 3, the hand 34 50 is placed to indicate the desired degree of humidity that is to be maintained in the surrounding atmosphere, and as long as the pointing hand 27 is to the left of such indication, as shown in Fig. 1, the circuit

through the batteries 38 and the vaporizers 55 41 will be closed so that the vaporizers in the various parts of the building will be supplying the desired moisture to the atmosphere. Upon the movement of the hand 27 toward the pointer 34, the contact spring 60 28 will slide upon the insulated portion of the hand 34 and open the circuit to cut out the vaporizers. It will thus be seen that any movement of the pointer 27 due to the decrease of the humidity in the atmosphere 65 will immediately close the circuit containing the vaporizers to actuate the vaporizers, and as soon as the atmosphere has been saturated to the desired degree of humidity, that the pointer 27 will be actuated due to the 70. expansive strips 12 and 17 to open the circuit and as before stated cut out the vaporizers.

What is claimed is:—

1. A humidostat, having a casing provided with a partition carrying a dial, a removable 75 transparent cover for the casing, an indicating hand, an arbor carried by the partition and carrying the hand, a plurality of humidity expanded strips, means for connecting one end of one strip to the partition, a lever pivoted intermediate of its ends to the partition and having one end pivotally connected to one end of one of the strips, said strips being connected together for coaction, and a flexible means for connecting 85 the other end of the lever to the arbor.

2. A humidostat, having a casing provided with a partition carrying a dial, a removable transparent cover for the casing, a pointing hand, an arbor carried by the 90 partition and carrying the hand, two humidity expanded strips, adjustable means for connecting one end of one strip to the partition, a lever pivoted intermediate of its ends to the partition and having its 95 terminals pivotally connected to the remaining end of the one strip and one end of the other strip, and adjustable means for connecting the free end of the remaining strip to the arbor.

In testimony that I claim the foregoing as my own, I have hereto affixed my signature in the presence of two witnesses.

LOUIS F. PERKETT.
